UNITED STATES PATENT OFFICE

2,519,809

PRINTING PLATE COATING MACHINE

Charles Zarkin and Bernard R. Halpern, New
York, N. Y., assignors to said Zarkin

Application August 30, 1946, Serial No. 693,846

9 Claims. (Cl. 91—42)

1

The invention disclosed in this patent relates to machines for applying the sensitive coatings to printing plates and generally known in the art as "whirlers."

Special objects of the invention are to provide such a machine with a top or cover construction which will afford ready inspection, placing and removal of the plates and which while providing full accessibility will not require much overhead clearance, even in the large size machines and will be so balanced and arranged that it may be easily opened and closed by one operator and remain in the various positions to which it may be shifted.

Other important objects of the invention are to provide efficient ventilation and drying for the plates.

Further special objects are to accomplish results indicated without adding objectionably to the bulk or cost of the machine.

Other desirable objects attained by the invention will appear in the course of the following specification, wherein the novel features of the invention are set forth and broadly claimed.

The drawings accompanying and forming part of the specification illustrate present commercial embodiments of the invention. The structure, however, may be modified and changed in various respects, all within the true intent and broad scope of the invention as herein defined and claimed.

Fig. 1 in the drawings is a plan view of a whirler incorporating the invention.

Fig. 2 is a side elevation of the same in closed position, with broken lines indicating the cover opening operation.

Fig. 3 is an enlarged broken and part sectional side view with broken lines indicating the cover opening operation.

Fig. 4 is an enlarged broken sectional detail on substantially the plane of line 4—4 of Fig. 1.

Figs. 5 and 6 are broken sectional details of one of the pivotal end connections for the balancing link, Fig. 6 appearing as on the line 6—6 of Fig. 5.

Figs. 7 and 8 are broken sectional details of the reversely disposed hinges for the inner and outer lid sections.

Figs. 9 and 10 are plan and side views respectively of a modified form of the invention.

In the whirler shown, the lid or cover is made in three sections, a narrow normally stationary section 10 affixed to the tub 11, an intermediate hinged section 12, and a front hinged section 13.

The intermediate or main section 12 is shown hinged to the stationary back section 10 by leaf hinges 14, on top of these sections, as shown in Fig. 7, and the front section 13 is hinged to the front edge of the intermediate section 12 by leaf

2

hinges 15, Fig. 8, at the under side of these sections.

This enables the hinges to break as shown in Fig. 3, with the middle section 12 folding upward and the forward section 13 folding downward with respect to the middle section supporting it.

The front section is caused to lift in substantially parallelism with the tub, that is, substantially horizontal at all times, by means of a positioning radius rod or link 16, Figs. 2 and 3, pivotally fulcrumed at 17 to a fixed strut 18 projecting upwardly at the back and forwardly over the top of the tub, and pivotally connected at its forward end at 19 to a lever 20 fixed at 21 on top of the front lid section and inclined upwardly and rearwardly from the hinge axis of the same.

The positioning link 16 is shown made up of two rod sections coupled by a turnbuckle 22 adjustable to maintain the parallelogram necessary to effect the horizontal lifting of the front cover section and to cause both movable cover sections to close down flat on the rim of the tub.

The lid made up of the two movable cover sections is counter-balanced in the illustration by two sets of weights 23, 24, Fig. 1, at the rear ends of lever arms 25, 26, attached to the top of the middle section 12 outwardly of the hinges 14 and projecting rearwardly from the hinge axis. The rearward ends of these weight carrying levers are shown in Fig. 1 connected by a cross bar 27, which may constitute an integral portion of such levers and in which event the levers and rearward connecting part may all be portions of a single U-shaped frame such as illustrated. For lightness and stiffness this U frame may be made of channel iron and the weights be in the form of heavy discs secured by through bolts 28 on opposite sides of such channel iron frame.

The lid sections may be made of channel or angle iron frames such as indicated at 29, Figs. 7 and 8, covered by sheet aluminum 30, this providing a desirably light but rigid and strong construction.

In the closed position, Figs. 2 and 3, the movable cover sections rest flat down on top of the rim of the tub and in this position over-balance the weights 23, 24, so as to remain firmly and securely closed during all ordinary operations of the machine.

To open the lid it is only necessary to apply lifting pressure to the movable front section 13. With proper counter-balancing only a relatively slight force is required to start the lifting movement and as such movement progresses the counterweights, through the leverage provided by the arms 25, 26, take control and complete the cover

opening movement and hold the cover in partly or fully opened relation. In the final position the whole interior of the tub is fully accessible and the movable cover sections are up out of the way and clear of all usual operations.

The closing of the cover may be effected by a slight downward pull on the front cover section, just enough force being necessary to overcome the lifting advantage of the counterweights in the lifted position of the cover.

For some installations it may be desirable to have foot-operated or foot-initiated cover closing or opening mechanism, such as illustrated in Figs. 1 and 2, and embodying a lever 31 pivoted on the base of the machine at 32, carrying a foot pedal 33 at its forward end and provided with an incline or cam 34 at its rearward end, arranged to reach under the weight 24 in its lowered position. With this construction a slight downward pressure on the pedal will effect the rocking of the counterweight lever 26 in a cover closing direction. Ordinarily, with the construction shown, it may be only necessary to initiate this cover closing movement, the lid then lowering by its own weight after passing the center where the counterweights lose control.

The parts may be made largely of structural steel such as angle and channel iron. Thus the fulcrum strut 18 for the equalizing rod 19 may be simply a length of channel iron such as shown in Figs. 3 and 4, bolted at 35 to the rim of the tub. Similarly, the bent lever 20, 21, may be a length of channel iron. The eyes 36 at the ends of the turnbuckle rods, may be pivoted on bolts 37 secured across the flanges of these channel irons, with spacer washers or sleeves 38 holding them in proper, freely pivoting alignment.

With all the advantages mentioned and others that will be apparent from this disclosure, the structure is relatively simple and inexpensive.

The parallelogram linkage in association with the counter-balancing levers, aids in stabilizing the smooth, easy opening and closing movements of the cover sections and enables the cover to stand or be held with light pressure at any intermediate position between the fully open and closed positions. The location of the closing pedal at the front of the machine enables the operator to conveniently control the cover opening and closing movements. With a slight lift on the front cover section, the cover may be started in the opening direction, finishing such movement under the pull of the counterweights as they gain advantage in the upward travel of the cover sections. Pressure on the foot pedal may be utilized to raise the cam 34 to check or stop the opening movement, in addition to or in place of the usual or normal purpose of initiating the cover closing movement. This foot pedal may be connected and arranged to initiate or effect the cover opening movement as well, or if desired, one pedal may be provided for opening and a second pedal for cover closing purposes.

While usual to have the rear cover section 10 fixed or stationary, this section may be hingedly or removably connected with the tub to provide further access for cleaning the rear or innermost portion of the tub.

In some machines and particularly those of the larger sizes, it may be desirable to incorporate ventilating and drying facilities. These are provided in the machine illustrated in Figs. 9 and 10 by equipping the front cover section 13 with ventilating louvers 40 and by the provision of a heater and blower 41 at the rear having a flaring

hood 42 for projecting heated air down through the top of the rear cover section 10.

The controls for the heater-blower unit and in fact for the main motor and such other accessories as the machine may have, such for example, as the red and white lights 43, 44 within the tub may all be located at the front of the machine as on one or more control panels such as indicated at 45.

10 In some instances it may be desirable to provide a catch for securing the lid in closed position, such as the gravity type latch indicated at 46, also a handle such as indicated at 47 for obtaining a convenient grasp on the front cover section.

15 In the larger size machines it may be desirable to reinforce the bent lid lifting lever 20, 21 as by struts 48 welded across the angularly related portions of such lever.

20 In the machine illustrated in Figs. 9 and 10 the counterweight levers 25, 26 are left disconnected at the rear and this machine is shown without the lid closing foot pedal. It should be understood, however, that these features may be incorporated in or left off either or both the machines illustrated.

25 The double hinged parallel motion lid construction provides maximum accessibility with a minimum of necessary overhead clearance. Rising horizontally as it does, the front lid section does not require any additional overhead space above that required for the opening of the intermediate cover section. Consequently, these whirlers may be located in places where it would be impossible to use a machine having a conventional one piece hinged cover.

30 What is claimed is:

1. A whirler cover comprising a relatively fixed, stationary cover section and coplanar movable cover sections, the movable cover section adjoining the stationary section being hingedly connected therewith on top of the cover and the movable sections being hingedly connected together at the under side of the cover, a lever extending from one movable cover section over the other movable cover section toward the stationary cover section, a fixed strut extending above and over the stationary cover section in line with the inner end of said lever, an equalizing link 35 pivotally connected between said strut and said lever and means for counterweighting the combined weight of the movable cover sections.

2. A whirler cover comprising a relatively fixed, stationary cover section and coplanar movable cover sections, the movable cover section adjoining the stationary section being hingedly connected therewith on top of the cover and the movable sections being hingedly connected together at the under side of the cover, a lever extending from one movable cover section over the other movable cover section toward the stationary cover section, a fixed strut extending above and over the stationary cover section in line with the inner end of said lever, an equalizing link 40 pivotally connected between said strut and said lever and means for counterweighting the combined weight of the movable cover sections including a U frame secured at opposite sides over the top of the movable section which is hinged to the stationary section and having the connecting portion of the same extended rearwardly beyond the hinge axis of said cover section, and weights on said side portions of the U frame.

3. A whirler top comprising a sectional cover, the sections of said cover being hingedly con-

70

nnected together and the inner one of said sections being fixedly supported, a lever on the outer of said cover sections extending rearwardly of the hinge line connecting said sections, a radius link pivotally connected therewith at one end and pivotally connected on a fixed fulcrum at the opposite end for maintaining the outer of said cover sections in generally horizontal relation in the opening and closing movements of the cover and means for counter-balancing the combined cover sections and arranged to overcome the combined weight as the cover sections are raised and to under-balance the cover sections as the same approach and reach the closed position, a foot treadle adjacent the base of the machine and means operated thereby for overcoming the advantage of the counter-balancing means in the raised position of the cover.

4. A whirler top comprising a fixed cover section, an intermediate cover section hinged on top of said fixed cover section and arranged to swing upwardly, a front cover section hinged to the under side of said intermediate cover section and arranged to swing downwardly as the cover sections open upwardly, linkage connected with said front cover section for maintaining the same in general horizontal relation while said cover sections are opening upwardly including a lever on the front cover section extending rearwardly of the hinge line connecting that section with the intermediate section and a radius rod pivotally connected with said lever, counter-balancing means acting on said intermediate cover section and means for imparting lowering, closing movement to said hingedly connected cover sections, said radius rod being pivotally connected at one end with said lever and pivoted on a fixed fulcrum at the opposite end.

5. A whirler comprising a tub, an upwardly lifting sectional cover hinged to said tub and including hingedly connected front and back cover sections, levers extending from said back cover section past the hinge axis of said section to the rear of the tub, weights on the rearward ends of said levers, a lever extending from said front cover section on an upward incline rearwardly beyond the hinging axis of said front cover section, a fulcrum strut at the back of said tub and an adjustable radius rod pivotally connected at its opposite ends with said fulcrum strut and with the rearward end of said upwardly inclined lever.

6. A whirler comprising a tub, a cover hingedly connected with said tub and comprising hingedly connected front, intermediate and back sections, linkage including a rearwardly extending lever on the front cover section and a radius rod pivotally connected therewith for maintaining the front cover section in substantially horizontal relation during opening and closing movements of the cover sections, a counter-balancing lever extending from the back cover section rearwardly of the hinging axis of the same and to the rear of the tub and leverage means engageable with said counter-balancing lever in the raised position of the cover sections for imparting lowering, closing movement to the cover sections, said back cover section being supported in stationary relation, said rearwardly extending lever being secured fast to the front cover section and projecting rearwardly toward the back cover section and said radius rod being pivotally connected at its forward end with said lever and pivotally fulcrumed on a fixed center at its rearward end.

7. A plate coating machine comprising a tub having rear, intermediate and front cover sections, said rear cover section being connected in stationary relation with the tub structure, a drier at the rear of the tub including a ventilating blower having an entrance way into said rear cover section, the intermediate cover section being hingedly connected with said rear cover section and the front cover section being hingedly connected with said intermediate cover section and means for controlling and counter-balancing opening movements of said intermediate and front cover sections including a rearwardly extending lever on the front cover section with a radius rod pivotally connected therewith and a rearwardly extending counter-balancing lever on said intermediate cover section, said rearwardly extending lever being secured fast to the front cover section and said radius rod being pivotally connected at its front end with the rearward end of said lever and pivotally fulcrumed on a fixed center at its rearward end.

8. A whirler comprising a tub having a back cover section at the back of the same, an intermediate cover section hinged on top of said back cover section and arranged to swing upwardly, a front cover section hinged to the under side of said intermediate cover section and arranged to swing downwardly as the cover sections open upwardly, linkage connected with said front cover section for maintaining the same in general horizontal relation while said cover sections are opening upwardly and counter-balancing means acting on said intermediate cover section.

9. A whirler comprising a tub having a back cover section at the back of the same, an intermediate cover section hinged on top of said back cover section and arranged to swing upwardly, a front cover section hinged to the under side of said intermediate cover section and arranged to swing downwardly as the cover sections open upwardly, linkage connected with said front cover section for maintaining the same in general horizontal relation while said cover sections are opening upwardly and counter-balancing means acting on said intermediate cover section, including a lever extending from said intermediate cover section rearwardly of the hinge thereof and a counterweight on the rearwardly extended end of said lever.
